UNITED STATES PATENT OFFICE.

ANDRÉ VARAUD, OF GENEVA, SWITZERLAND.

MECHANICAL FUSE FOR ARTILLERY PROJECTILES.

Application filed June 17, 1925, Serial No. 37,698, and in Switzerland August 2, 1923.

This invention relates to clockwork operated fuses for artillery projectiles of the type in which the release or unlocking of the striker is controlled by a rotary setting member, the angular position of which can be set before firing and which during the flight of the projectile is driven by a clockwork having a power spring in a direction opposite to the one in which the setting is effected.

10 In one prior construction of this type it has been proposed to provide a pivoted disk, controlling the striker and adapted to be released by a rotary crown member integral with the spring drum of the fuse and with an internally toothed portion driving the escapement regulating mechanism of the fuse.

As shown and described in my copending application Serial Number 38,498 filed June 20, 1925, it is proposed to mechanically connect a rotary set member to the drive shaft of the clockwork of the fuse by means of a reducing gear. The objects of this construction are threefold:

1. To considerably reduce the motive power required for controlling the unlocking of the striker.

2. To enable the drive shaft of the clockwork mechanism to perform several winding revolutions for one setting revolution of the rotary setting member and to consequently reduce the required multiplication between the drive shaft and the last moving member of the gear train of the clockwork mechanism, that is to say the escapement wheel.

3. To increase the motive power storage capacity of the main spring of the fuse.

The apparatus made in accordance with my present invention preferably consists in the combination of a rotary setting member in the form of an internally toothed member or crown piece with a reduction gear connecting the drive shaft of the clockwork thereto.

The attached drawing represents by way of example one embodiment of the object of the invention.

Fig. 1 is an axial partial section of the fuse to which the said object of the invention has been applied. This section is made on the line I—I of Fig. 2.

50 Figs. 2 to 4 are cross sections on the lines II—II, III—III and IV—IV respectively of Fig. 1.

Fig. 5 is a similar section as that shown in Fig. 4 showing the position of the retaining member of the striker at the moment of liberation of the latter.

Fig. 6 shows a first working form of the retaining member of the locking lever in active position, whilst

Fig. 7 shows the release position of said lever.

The Figures 8 to 10 are views of a second constructional form of said retaining member in different positions.

The Figures 11 and 12 are vertical sections 65 on a larger scale on the line VI—VI of Fig. 8.

In the drawing which shows only those of the parts of the fuse which are directly associated with the object of the invention, it will be seen that the striker 1 is guided along 70 its whole length in a sleeve 2 and is subjected to the action of a strong percussion spring 3 surrounding the sleeve 2 and acting on a collar or shoulder presented by the striker near its point.

75 The subject matter of Figs. 1 to 5 inclusive is shown and described in my copending application, Serial No. 712,960 filed May 13, 1924.

This striker is normally locked in its cocked position (Figs. 1 and 4) by a retaining member or bolt 4, taking into a lateral notch 5 provided for in the striker body over about one half of its transverse section. This locking bolt 4 is pivotally mounted about the shank of a stop screw 6 and is subjected to the action of a pulling-off spring 7 bearing against a pin 8 which extends perpendicularly from the bolt 4 so as to counterbalance the resistance which the percussion spring 3 exerts on this bolt 4.

80 Up to the moment of firing the bolt 4 is normally held in its locking position against the action of spring 7 by a drop plug 9 fitted with a spring sleeve 10 and adapted to drop 95 out of position in a well known manner by inertia at the moment of firing, but during the whole flight of the projectile this bolt 4 is retained in its active or locking position against the action of the spring 7 then aided 100 by that of the centrifugal force by an internally toothed crown piece 11 rotating freely in an annular groove 12 provided in the bottom of the casing 13 of the clockwork mechanism.

105 In the external wall of this groove 12 are arranged at 120°, one to the other, three notches 14 in which operate three balls or rollers 15 by which the periphery of the crown piece 11 is supported. The upper face of said crown 11 bears also on balls 16 (of which in Fig. 1 one only is shown in dotted lines)

lodged in grooves of the clockwork housing 13.

Due to these two ball or rolling races the friction opposed to the rotation of the crown 5 11 is reduced to a minimum.

An inner tooth rim 17 of the crown 11 is in constant mesh with a pinion 18 keyed on an auxiliary setting shaft 19 which moreover carries a gear wheel 20 meshing with a 10 pinion 21 keyed on the lower extremity of the drive shaft 22 of the fuse. The ratios of the gears 17, 18, 20 and 21 are such as to enable the driving shaft 22 to perform several revolutions for a single revolution of the crown 15 piece 11.

In the cylindrical edge of the crown piece 11 against which a nose 24 of the locking bolt 4 comes to bear at the moment of the departure of the projectile is provided a slot 23 on 20 a level with the bolt 4.

The unlocking or liberation of the striker 1 takes place when this slot 23 happens to register with the nose 24 of bolt 4.

The crown piece 11 is in addition provided 25 with a catch 26 projecting radially towards its center and cooperating with the drop plug or weighted pin 9 (Fig. 4) to prevent up to the moment of firing any rotation of the toothed crown in clockwise direction, that is to say for rendering impossible any accidental 30 unlocking of the striker.

In order to avoid, in the case that the projectile to which the fuse is applied, were dropped during its transport or handling, 35 that the drop-plug or weighted pin 9 is not accidentally withdrawn, a notch 9' (Figs. 1 and 4) is provided for in the head of said pin, into which the catch 26 is engaged at the termination of the manufacture of the fuse 40 in such a manner as to thereby render any accidental displacement of the drop-plug or weighted pin 9 impossible as long as the catch 26 has not been displaced in the counter-clockwise direction, that is to say as long 45 as the fuse has not been timed.

The function of this release or unlocking mechanism of the striker is as follows:

On the winding of the power spring 27 of the clockwork movement of the fuse the 50 toothed crown member 11 is driven to rotate in counter-clockwise direction through an angle in proportion to the duration of flight which it is desired to be obtained. This angle, as in the case of several of known mechanical fuses, cannot attain 360° , but—contrary to what exist in prior fuses—owing to the reduction gear 21, 20 and 18, 17, this fact 55 does not prevent the main shaft 22 from performing several winding revolutions.

60 In such a manner it is possible to store up in the power-spring 27 a motive power which is sufficient to obtain firing ranges of relatively very great durations, and to subdivide these durations into a very large number of setting positions for different ranges.

Moreover, also owing to this demultiplication, the effort of the motive power required for controlling the release or unlocking of the striker is considerably reduced as compared with known fuses in which the rotary controlling member of the unlocking of the 70 striker is integral with the driving member of the clockwork movement.

Whilst this counter-clockwise rotation of the crown member 11 takes place which rotation determines the setting of the time for the ignition of the fuse, the bolt 4 and the drop-plug or weighted lever 9 remain stationary 75 in their respective operative positions (shown in Figs. 1 and 3).

It should be observed that during the re-winding and the simultaneous setting of the fuse thus effected, the nose 24 of the bolt 4 is not in contact with the crown 11, whereby the latter is enabled to be rotated in a very 80 easy manner.

At the moment of firing the drop-plug or pin 9 disappears in its container in the known manner by inertia and the nose 24 comes to bear against the interior face of the crown 90 11 which thereupon is driven by the clockwork movement to return in clockwise direction through the travel traversed but in the opposite sense during its setting travel increased, however, by the small angle required 95 for bringing the notch 23 from the position according to Fig. 4, to the release position as shown in Fig. 5.

The notch 23 having reached this latter 100 position, the bolt 4, under the combined action of its spring 7 and of the centrifugal force, liberates instantaneously the striker 1.

It is to be noted that the fact of employing the crown 11 with an internal toothed 105 17 permits to utilize for this member, the diameter of which is to be as large as possible, nearly the whole space at disposal in the interior of the body of the fuse.

Since the friction between the nose 24 and the crown 11 during the operation of the 110 clockwork is proportional to the angular velocity of the projectile,—as the lever 4 is subjected to the action of the centrifugal force,—it may prove useful in the case that the fuse is fitted to a projectile of a great angular velocity to employ an intermediate member which prevents any direct contact between the nose 24 and the crown 11 during nearly the entire trajectory whilst said direct contact may be established a few moments before 115 the arrival of the notch 23 opposite the nose 24. In this manner the power required for driving the crown 11 is considerably reduced while the device preserves its precision as regards the release of the striker.

According to the Figs. 6 and 7 the intermediate member comprises a hook 28, mounted so as to oscillate about the striker 1. This hook holds normally the lever 4 out of contact from the crown 11 owing to a notch 120 130.

27 in which the pin 8 normally is lodged while the striker 1 is in cocked position. The arrangement is such that during the operation of the clockwork a few moments before the 5 releasing notch 23 comes to register with the nose 24 of the locking lever 4, a pawl 26' presented by the said crown comes to abut against the free end of the hook 28 and displaces the same, so to force the pin 8 out of 10 its recess 27 (position as represented in Fig. 1). The nose 24 comes to rest an instant on the crown 11 until the moment when the notch 23 comes opposite and permits the liberation of the striker 1.

15 According to the second constructional form as shown in Figs. 8 to 12, the hook 28 of the first form is replaced by a pin 29 mounted freely in the frame of the clockwork. This pin 29 is held in its operative 20 position by a spring 31 and in this position retains by its end 30 the nose 24 of the lever 4 spaced from the crown. In order to disengage the lever 4 from the pin 29, the latter is provided with an inclined plane 32 against 25 which the pawl 26' of the crown operates at the moment in which it comes to register with the pin.

Owing to this action the pin 29 withdraws and is displaced in a perpendicular plane in 30 regard to lever 4 and abandons the latter to the action of its spring and of the centrifugal force. Since this liberation of the lever 4 by the pin 29 is effected some hundredths of a second before the notch 23 arrives opposite 35 the nose 24, the contact of this nose on the periphery of the crown takes place only during this infinitely short period of time a fact from which results the nearly complete suppression of the perturbating causes of the 40 operation of the clockwork which up to now have been due to the friction of the locking device of the striker.

Besides, in order to progressively diminish the retaining surface of the lever 4 with 45 regard to the striker until the moment of the release, the internal border of the crown is progressively made thinner as at 33, so as to constitute on the side of the notch an inclined plane on which the nose of this lever 50 slides.

What I claim is:

1. In a projectile of the type described, a drive shaft, a revolute member, a striker, a locking device for normally maintaining the striker in an initial inoperative position, means connecting the drive shaft and revolute member whereby when the drive shaft is turned in one direction the revolute member is turned to a set position and when the drive shaft turns in the opposite direction the revolute member is turned thereby a predetermined portion of a revolution in the other direction to determine the moment of release of the striker, means for normally 55 maintaining the locking member out of con-

tact with the revolute member until just before the release of the striker, and means for actuating the locking member causing the same to co-operate with the revolute member for the release of the striker. 70

2. In a projectile of the type described, a drive shaft, a revolute gear, a striker, means connecting the drive shaft and revolute gear whereby when the drive shaft is turned in one direction the revolute gear is turned to a set position and when the drive shaft turns in the opposite direction the revolute gear is turned thereby a predetermined portion of a revolution to determine the moment of release of the striker, a locking bolt for 80 normally maintaining the striker in an inoperative position, means for maintaining the locking bolt out of contact with the revolute gear until just before the striker is released, and means for actuating the locking bolt when released causing the same to co-operate with the revolute gear in releasing the striker. 85

3. In a projectile of the type described, a drive shaft, an internal gear having a recess therein, a striker, a locking bolt for normally maintaining the striker in an initial inoperative position and when released to enter the recess in the internal gear to free the striker, means connecting the drive shaft and the internal gear whereby when the drive shaft is turned in one direction the internal gear is turned to a set position and when the drive shaft turns in the opposite direction the internal gear is turned thereby a predetermined portion of a revolution in the other direction to determine the moment of release of the striker, means for maintaining the locking bolt out of contact with the internal gear until just before the striker registers with the recess in the internal gear, a device by which the aforesaid means is released just before the locking bolt registers with the recess in the internal gear, and means operative when the aforesaid means are released 95 for actuating the locking bolt permitting a portion thereof to enter the recess in the internal gear and thereby release the striker. 100

4. In a projectile of the type described, a drive shaft, a crown piece having a recess therein and provided with internal gear teeth, a striker, a locking bolt normally in engagement with the striker to maintain the same in an initial inoperative position, the said locking bolt having a free end adapted to engage 115 in the recess in the crown piece, a drop plug for maintaining the said locking bolt in its initial position, the said drop plug being automatically operative upon firing the fuse to free itself from the said locking bolt, means connecting the said drive shaft with the internal gear of the crown piece whereby when the drive shaft is turned in one direction the crown piece is turned to a set position and when the drive shaft turns in the opposite 120 125 130

- direction the crown piece turns a predetermined portion of a revolution in the other direction until the free end of the locking bolt is in position to engage in the recess in the crown piece, means for maintaining the locking bolt in a position in which its free end does not contact with the crown piece during the major portion of the return movement thereof, and means operative momentarily before the end of the locking bolt registers with the recess in the crown piece for releasing the locking bolt and actuating the same to cause the free end thereof to enter the said recess in the crown piece thereby freeing the locking bolt from the striker.
5. In a projectile of the type described, a drive shaft, a crown piece having a recess therein and provided with internal gear teeth, a striker, a pivoted locking bolt normally in engagement with the striker to maintain the same in an initial inoperative position and having a free end adapted to engage in the recess in the said crown piece, a drop plug for maintaining the said locking bolt in its initial position, the said drop plug being automatically operative upon firing the fuse to

free itself from the said locking bolt, means connecting the said drive shaft with the internal gear of the crown piece whereby when the drive shaft is turned in one direction the 30 crown piece is turned to a set position and when the drive shaft turns in the opposite direction the crown piece turns a predetermined portion of a revolution in the other direction until the free end of the locking 35 bolt is in position to engage in the recess in the crown piece, means for maintaining the locking bolt in a position in which its free end does not contact with the crown piece during the major portion of the return movement thereof, means operative momentarily 40 before the end of the locking bolt registers with the recess in the crown piece for releasing the locking bolt and actuating the same to cause the free end thereof to enter the said recess in the crown piece thereby freeing the locking bolt from the striker, and means for actuating the striker after the same has been freed from the locking bolt.

In testimony whereof I affix my signature.

ANDRÉ VARAUD.
